TOOLHOLDER

Edward Thompson Pringle, Jr., Brooklyn, N. Y.

Application May 1, 1944, Serial No. 533,560

2 Claims.

(Cl. 29—96)

This invention relates to a device for holding tools and more especially cutting tools such as used on lathes, one of the objects being to provide a holder which permits minute adjustment of the held tool toward or from the work and which has a further means whereby the tool is held securely in place following the adjustment and without danger of shifting as a result of the vibration to which it is subjected in use.

A further object is to provide a structure of this character which is simple and compact in construction and which can be operated readily for the purpose of adjusting and gripping the tool.

It is a fact well known that in metal working, where minute cutting, etc. of the work is necessary, difficulty has been experienced in effecting the proper adjustment of the tool and holding the tool in its adjusted position, this being particularly true where measurements in thousandths of an inch are required.

The present invention has for an object the provision of means whereby the necessary minute adjustment can be effected, can be indicated, and can be maintained.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawing the preferred form of the invention has been shown.

In said drawing:

Figure 1 is a central longitudinal section through the holder, a tool being shown in position therein.

Figure 2 is a top plan view thereof.

Figure 3 is an end elevation.

Figure 4 is a section on line 4—4, Figure 1, the adjusting block being shown in elevation.

Referring to the figures by characters of reference, 1 designates the body of the holder which can be in the form of a block of any suitable size and shape whereby it can be mounted properly on the particular metal-working machine with which it is to be used. This block is provided with an angular opening 2 extending longitudinally therethrough. The bottom of the opening is cut away for a portion of its length but throughout the width of the opening to provide an elongated recess 3 the bottom 4 of which

is inclined downwardly toward the open front end of the recess. Fitted snugly within this recess is a wedge 5 the top surface of which is parallel with the longitudinal axis of the opening 2, and within the back or small end of the wedge is a bore 6 the wall of which is screw-threaded so that it can be engaged by an adjusting screw 7. This screw has an elongated smooth stem 8 mounted for rotation in a bore 9 extending from the small end of the recess 3 to the back end of the body 1 and a head 10 constitutes the outer or exposed end of the shank or stem 8. An annular groove 11 is provided in the stem 8 and projecting thereinto is a retaining screw 12 or the like the head of which is located at one side of the body where it can be reached readily for feeding the screw into or out of the groove, thereby to hold the stem 8 against longitudinal movement.

20 A longitudinal slot 13 is provided in the top of the body 1 and opens downwardly into the opening 2. An adjusting screw 14 is extended longitudinally of the slot and has a reduced end portion 15 journalled in one wall of the slot while at the other end of the tool, is a stem 16 mounted for rotation in the opposite wall of the slot. This stem 16 is provided with a head 17 at the forward end thereof and is also provided with an annular groove 18 into which projects a retaining screw 19, the head 20 of which is located where it can be reached readily at one side of the body 1. This screw serves to hold the adjusting screw 14 against withdrawal from body 1 under working conditions.

35 An index or pointer 21 is extended from the head 17 and cooperates with an annular series of graduations 22 on the adjacent surface of the body 1. These graduations can be suitably designated and in practice each graduation can represent an adjustment of a very small unit of measure such as a thousandths of an inch.

40 An adjusting block 23 is located in the slot 13 and is mounted on the screw 14. This block has a tongue 24 extended therefrom into the opening 2.

The cutting tool has been indicated at 25 and can have its active end of any suitable design, capable of doing the work required. The width of this tool is such as to insure a working fit against the sides of the opening 2 and the top and bottom surfaces of the tool are parallel. A notch or recess 26 is provided in the top of the tool and is proportioned to receive and be snugly engaged by the tongue 24.

55 In practice the wedge 5 is fed outwardly by

turning the screw 7 in one direction. Thus its top surface is brought below the level of the bottom wall of opening 2. The block 23 is inserted into the slot 13 so that its tongue 24 will drop into the recess 26 in the tool and thereafter screw 14 is inserted longitudinally into its bearings and becomes properly seated therein after being fed through the block 23. When the screw has been brought to its proper position, the retaining screw 19 is directed into the groove 18 and thereafter, by rotating screw 14, the tool 25 can be fed in either direction. The wedge 5 is adjusted inwardly so as to lightly engage the tool. The tool is then adjusted minutely so as to make a cut of the desired depth after which the wedge 5 is adjusted inwardly a sufficient distance to clamp the tool tightly in place, thereby insuring against accidental shifting of the tool following its minute adjustment. Obviously, by giving a slight turn to the screw 7, the wedge can become slightly released from the tool and by then giving a desired turn to the head 17 to insure a cut of the proper depth as indicated by the cooperating elements 21 and 22, the tool can again be gripped by adjusting the wedge as already explained.

What is claimed is:

1. A tool holder including a body having an opening extending thereto and a slot communicating with the opening, an adjusting screw mounted for rotation in said body and extending

longitudinally of the slot, means for holding said screw against longitudinal displacement, a member mounted on and shiftable by the screw and slideable longitudinally of the slot, said member projecting into the opening, cooperating means on the screw and body for indicating the extent of movement of the member by the screw, and a tool slidably mounted in the opening and having a notch into which said member is extended.

2. The combination with a tool having a recess extending thereto, of a holder for the tool including a body having an opening into which the tool is extended, there being a longitudinal slot in the body communicating with said opening and a recess in the body opposite to the slot, said recess having an inclined bottom, adjusting screws extending across the slot and longitudinally thereof and into the recess respectively, means for holding the respective screws against longitudinal movement, said screws being mounted for rotation, a block in the slot and on one of the screws, said block having an integral portion extended into the recess in the tool, a wedge within the recess and bearing on the inclined surface thereof, said wedge having a surface parallel with the longitudinal axis of the opening, said wedge being in engagement with and adapted to be adjusted by the other screw thereby to clamp upon the tool within the opening.

EDWARD THOMPSON PRINGLE, JR.
